UNITED STATES PATENT OFFICE.

FRANCIS ASBURY BREWER, OF KIRKVILLE, NEW YORK.

RAIL-JOINT.

SPECIFICATION forming part of Letters Patent No. 664,620, dated December 25, 1900.

Application filed October 7, 1899. Serial No. 732,883. (No model.)

To all whom it may concern:

Be it known that I, FRANCIS ASBURY BREWER, a citizen of the United States, residing at Kirkville, in the county of Onondaga and State of New York, have invented a new and useful Rail-Joint, of which the following, taken in connection with the accompanying drawings, is a full, clear, and exact description.

10 My invention relates to improvements in rail-joints in which the ball, neck, and base of the rail at its ends are vertically, longitudinally, and laterally cut to form a splice, with the object in view of forming a joint that will prevent pounding at the joints and make a firm and secure joint for rails for railroad purposes.

With this object in view my invention consists in the detailed construction and arrangement of the parts as herein described and shown.

In the accompanying drawings, Figure 1 is an isometrical representation of my complete invention, showing the ends of two rails 25 united. Fig. 2 is a cross vertical section of my rail-joint on line $\alpha\alpha$ of Fig. 1. Figs. 3 and 4 are isometrical representations of the two ends of a rail, showing substantially the form in which the ends are constructed for 30 my rail-joint. Fig. 5 is an isometrical representation of my rail-joint with the side or fish plates removed. Fig. 6 is a representation of the side or fish plates, and Fig. 7 is a representation of the plate used upon the top 35 of the ties and under the ends of the rails at the joints.

Like characters refer to similar parts throughout the several views.

A and A' represent the opposite ends of the 40 two rails used to form my rail-joint.

B represents side plates used to stiffen the joint.

C represents plates placed on top of the rail-ties under the joint to keep the base of the 45 rails on the same plane.

D represents the rail-ties.

a is a reinforcement or thickened portion of the neck of the rail.

b is a lug, and c is a sink for the reception

of the lug b and is made some longer than 50 the lug to allow for expansion and contraction of the rail in warm and cold weather.

d represents holes for the reception of the bolts e.

In the construction of my rail-joint it is to 55 be observed that I provide the neck of the rail for a short distance on the ends and on either side of the rail with reinforcements a, thereby overcoming any weakening of the neck of the rail by cutting or splitting the 60 same for the purpose of the splice, as shown. This reinforcement of the neck also enables me to make the sink c to receive the lug b without impairing the necessary strength of the neck, the said lug fitting closely within 65 the said sink latitudinally, thus keeping the tops of the rails when connected uniformly even. In the formation of the splice for my rail-joint it is also to be observed that a line from the point 1 to point 2 on the rail falls 70 practically in the center of the tread of ball of the rail and that from point 2 to point 3 a line turns from the center of the tread of the rail at a gradual divergence, thus preventing any sudden transition of a wheel from the 75 tread on one rail to the tread on the other, and thereby avoiding pounding at the joints, which was to be accomplished.

In construction for use I use the side or fish plates B and secure the joint therewith 80 by means of bolts e, passed through the holes d provided therefor, and rest the base of rail at the joint upon the metal plates C, which are secured to the rail-ties in the ordinary way, thus forming a complete union of the 85 rails and which constitutes my complete rail-joint.

Having thus pointed out the various parts of my invention and shown its construction and use, what I claim as my invention, and 90 desire to secure by Letters Patent, is—

A rail-joint composed of rails A, A', having reinforced web or neck a, at the ends of the rail; the ball, web or neck and base of the rails at the ends, cut vertically, longitudinally and laterally to form a splice, provided with sink c for the reception of lug b; the lug b and holes for the passage of bolts 95

e, and plane angular fish-plates embracing the neck or web and base of the rails on opposite sides of the rails at the joint, and bolts to secure the various parts to one another substantially as shown and described.

In witness whereof I have hereunto set my hand, at the city of Syracuse, in the county

of Onondaga and State of New York, this 19th day of July, A. D. 1899.

FRANCIS ASBURY BREWER.

Witnesses:

C. TUCKER,

M. BENDIXEN.
